[57] **CLAIM**

The ornamental design for a closure for adjusting an automobile shoulder strap, as shown and described.

DESCRIPTION

FIG. 1 is a perspective view of an closure for adjusting an automobile shoulder strap according to the present invention, shown in an open condition;

FIG. 2 is a perspective view shown in a closed condition;

FIG. 3 is an open top view thereof;

FIG. 4 is a closed top view thereof;

FIG. 5 is an open bottom view thereof;

FIG. 6 is a closed bottom view thereof;

FIG. 7 is an open front view thereof;

FIG. 8 is an open rear view thereof; and,

FIG. 9 is an open right view thereof, wherein the left view is a mirror image of FIG. 9.
